GAS BURNER CONTROL MEANS

William D. Antrim, Cleveland Heights, Ohio, assignor, by mesne assignments, to Carrier Corporation, a corporation of Delaware

Application November 29, 1954, Serial No. 471,672

12 Claims. (Cl. 158—132)

This invention relates to means for controlling operation of a main gas burner from its fuel source, characteristic applications of which are in the oven or broiler of a gas cooking range, or in other gas-fired appliances such as a heater or clothes dryer.

The invention pertains to the class of control means including a safety pilot burner in igniting relation to the main burner, a safety valve in the main gas line arranged for automatic opening and closing dependent on operation of the safety pilot burner, through the medium of a thermally responsive device, and a constant pilot burner in igniting relation to the safety pilot burner.

Objects of the invention are to provide that the constant pilot may be of minimum capacity, be easily and quickly put into operation, and be protected against outage during normal cycling of other elements of the installation.

Another object is to provide that, upon outage of the constant pilot, as during a standby period, its own supply of gas as well as that to the constant pilot and the main burner be automatically cut off, so as to insure complete safety for the entire apparatus; yet constant pilot outage during a period of operation of the safety pilot will permit continued operation thereof, with possible constant pilot relight therefrom.

The invention contemplates that the pilot burners and their automatic valves may be located in the combustion chamber of the main burner and therefore subject to high ambient temperatures, as during main burner operation, much beyond ambient temperatures during intervening periods; and a further object of the invention is to insure consistent operation of the apparatus, independent of its ambient temperatures.

The invention embraces the provision and employment of novel thermally responsive means, of dual character and arrangement such that the main burner safety valve has operation solely responsive to the safety pilot burner and independent of ambient temperature, whereas the safety and constant pilot valves may have operation not only responsive to the constant pilot burner but also affected to some degree both by ambient temperature and by the safety pilot burner. To these ends the dual thermally responsive device includes novel primary and secondary units, and relation therebetween, as will hereinafter appear.

Still another object is to combine in a compact relationship in a rugged unitary device, the two pilot burners, the three automatic valves, and the dual thermally responsive means effective to actuate the valves dependent upon pilot burner operation; all in arrangement wherein relatively delicate parts have protection, yet necessary adjustment thereof is provided and maintained.

Still another object is to provide an arrangement, wherein the two burners and the three valves include parts which are portions of a common base structure, upon which the dual thermally responsive device is mounted for control of the valves by the burners.

Further objects and advantages will be apparent from the following description taken in connection with the

2

accompanying drawings, which disclose an exemplification of the invention particularly adapted for employment within the oven of a cooking range.

In the drawings,

- 5 Figs. 1 and 2 are views of a pilot burner assembly which includes automatic main, safety pilot, and constant pilot gas supply valves; Fig. 1 being generally in plan but showing the safety valve cover removed, and the pilot burner valves in longitudinal section, as indicated by the line 1—1 of Fig. 2, and Fig. 2 being in elevation but partly broken away to show details of construction;
- 10 Fig. 3 is a detail in sectional elevation of pilot burner parts appearing in Fig. 1, as indicated at line 3, Fig. 1;
- 15 Fig. 4 is a view in sectional elevation generally as in the plane of line 4—4 of Fig. 1;
- 20 Fig. 5 is a view in isometric perspective of the dual thermally responsive device employed, together with main burner safety valve parts actuated thereby, the valve housing being indicated in broken lines;
- 25 Fig. 6 is a conventionalized diagrammatic view indicating the principal parts, the circuit arrangement in which they are employed, and their relationship therein, the combustion chamber in which certain of the parts are located being indicated by a broken line; and
- 30 Figs. 7 to 11 inclusive illustrate details of the dual thermally responsive device, Fig. 7 as a plan, Fig. 8 as in transverse section, as indicated by line 8—8 of Fig. 7, Fig. 9 in side elevation, Fig. 10 in end elevation, and Fig. 11 as viewed from the bottom.
- 35 With reference now to the drawings, and first to Figs. 1 to 4 thereof, a base structure is provided comprising principally a base casting generally indicated at A, which may be of cast iron, and shield means 3, firmly secured thereto by rivets 3a, and which may be of heavy gauge stainless sheet steel.
- 40 The base A, together with the shield means 3, constitute a common rigid base structure for other parts of the unitary control device, as will appear hereinafter.
- 45 The safety valve may be of ball type including the ball 5 which seats in a horizontally disposed circular opening in its valve body 1, which latter constitutes a portion of the base casting A.
- 50 The safety pilot means 2 includes a passage in the base A, as shown in Figs. 1 and 4, and a tip 6 ported as indicated at 7, Figs. 1, 2 and 3.
- 55 The portion 7 includes an end portion to be in igniting relation to the main burner to be served by the device, and side portions to be in igniting relation to a constant pilot burner and energizing relation to a thermally responsive device, all such portions being arranged for coincident operation as known in the art.
- 60 The shield means 3 is generally of elongated form, U-shaped in transverse section, extends along and laterally beyond the base A to provide a hollow as indicated best in Fig. 4.
- 65 The dual thermally responsive device, generally indicated at 4, is disposed along and within the hollow provided by the shield 3. It is of elongated form, and is mounted on the base A by the shield 3, with an end secured as by rivets 13 to the web of the shield adjacent the pilot burner 2, and a free end adjacent the safety valve.
- 70 Actuating connection is provided effective between the free end of the device and the ball 5 of the valve such that on operation of the safety pilot burner 2, to energize the device 4, the ball 5 will be unseated to open the main burner safety valve 1, and upon safety pilot outage the valve will close by gravity.
- 75 Arrangement for such actuation of the valve is illustrated in Fig. 5 as well as indicated in Fig. 1, and includes the rock shaft 8 mounted in the valve body, a pin 9 mounted on the free end of the thermally respon-

sive device, a forked lever 10 on the rock shaft 8 outside the valve body and engaging the pin 9, and an arm 11 within the valve body to engage the ball 5.

What has thus far been described is known in the art, as exemplified in:

Patent No. 2,487,963, issued November 15, 1949 to Cerny et al., for "Safety Control for Oven Pilots and Main Burners."

Patent No. 2,487,969, issued November 15, 1949 to Higley, for "Ball Valve Safety Pilot Burners," and

Patent No. 2,520,399, issued August 29, 1950 to Higley, for "Pilot Burner and Thermally Controlled Valve Therefor."

It should be noted that the above set forth operation of the safety valve dependent upon operation of the safety pilot is had substantially independent of the ambient temperature to which the assembly is subject, as will more specifically appear hereinafter.

With reference now particularly to Figs. 5 to 11, the thermally responsive device of this invention is of dual character comprising a related pair of thermally responsive units, including a lower one for the previously described actuation of the safety valve 1, and constituting a primary unit 4a, and the other, generally thereabove, constituting a secondary unit 4b.

The primary unit, generally indicated at 4a, at its base end 12 may be provided on one side with openings 13 by which it is secured to the shield 3, as by rivets or welding.

The primary unit 4a is U-shaped in transverse section at its base end 12, as indicated Figs. 5 to 10, is provided with a slot 14 along the web of its U for a substantial distance adjacent the base end, and is U-shaped for a substantial distance beyond the slot toward its free end. Thus, along its slot 14 the unit includes a pair of legs 15 in facing spaced relation, separated from each other by the slot 14 but integrally related with each other by the webs of the U therebeyond.

In the assembly, Figs. 1 and 2, the porting 7 of the safety pilot burner 2 is such that its operation will heat the near leg 15 of the primary unit 4a. The heat energy thus applied to one of the legs 15 will cause this leg to elongate relative to the other leg, which is relatively cooler, and being integral of the same coefficient of expansion. Therefore, the primary unit thus energized, will effectively convert the input of heat energy to one leg into mechanical energy, and flex to cause its free end to move and open the safety valve. Upon pilot outage both legs will be subject to the same ambient temperature regardless of its amount, the primary unit thus de-energized will strengthen, and the valve will close.

The primary unit 4a may be recognized as generally of the type disclosed in Patent No. 2,455,306, issued November 30, 1948 to Frank R. Higley, for "Thermally Responsive Unit."

The secondary unit 4b also includes a pair of leg members arranged in slightly spaced relation to provide a slotted effect as at 16, Figs. 5 and 7. One of its leg members is integral with that leg member 15 of the primary unit 4a which is exposed to the safety pilot burner, and joins such primary unit leg member intermediate the ends of the slot 14. It has an offset portion for a substantial distance along its length for its described slotted effect. The other leg of the secondary unit 4b is flat and secured to the first-named leg beyond the ends of the offset portion of the latter, as by welding. The straight leg of the secondary unit may if desired be of a metal having a slightly lower coefficient of expansion than that of the other three legs of the dual thermally responsive device, so that the free end of the secondary unit 4b will have a slight increment of movement responsive to rise in ambient temperature, in the same direction that the primary unit 4a is caused to move by heat from the safety pilot burner.

It will be apparent also that heat applied to the offset

75

The safety valve 1 is arranged in a main gas line 30

leg of the secondary unit 4b will energize it to impart an increment of movement in that direction, because of differential in temperature between the two legs as described in connection with the primary unit 4a.

Moreover, since the effective base of the secondary unit 4b is upon a leg 15 of the primary unit 4a, some of the movement of the primary unit 4a will be imparted as a third increment to the secondary unit 4b.

Thus, the free end of the secondary unit 4b may have differentially related and possibly cumulative increments of movement responsive to heat input, either

(1) To both of its own legs due to rise in ambient temperature,

(2) To its offset leg only, as from the constant pilot burner, and/or

(3) To the near leg of the primary unit 4a, from the safety pilot burner.

Further according to this invention, the secondary unit 4b of the dual thermally responsive device, is employed for coincident automatic control of a pair of twin valves.

With reference now particularly to Figs. 1 to 4 of the drawings, these twin valves include a safety pilot valve 18 and a constant pilot valve 19 having a common valve body 20, which as illustrated may be integral with the main base casting as a portion thereof.

Each of these twin valves is of the so-called normally open type, that is, either will permit gas flow indicated by the arrows in Fig. 1, unless closed by depression of a plunger 22.

Further details of construction of these valves are not material here, but as indicated in the drawings, they employ metal diaphragms well known in the art, and are of slight capacity.

The plungers 22 of the twin valves have recessed heads as indicated Fig. 1, and are interconnected as by an operating yoke 23, which has fingers arranged to seat in the head recesses, a stem portion extending downwardly and through a suitable opening in the shield 3 past the free end of the secondary thermally responsive unit 4b, and therebelow has loose forked bearing on the end of an adjusting screw 24, which is mounted in the valve body 20. The yoke stem portion, serves as a lever, fulcrumed on the screw 24, actuatable by the secondary unit 4b, with multiplying effect on the twin valves 18 and 19, and is adjusted by the screw 24 to provide that these valves will open upon slight energization of the secondary unit 4b from any of the three sources previously enumerated, and will otherwise be maintained closed by the secondary unit, such valve operation being fast and automatic.

The safety pilot valve 18 has an outlet connection 25 to the inlet of the safety pilot burner 2 which may be drilled in the main base casting, as indicated in broken lines in Fig. 1.

The constant pilot valve 19 has a drilled outlet forming the base portion of a constant pilot burner 26, which latter may include a small tube set into the valve body 20 portion of the base A and leading therefrom to a location within the shield 3, adjacent the porting 7 of the safety pilot burner to be in igniting relation with the latter, and also in heating relation to the near "hot" or offset leg of the secondary thermally responsive unit 4b.

The shield 3 is provided with a suitable top opening 27 for ignition access to the constant pilot burner 26 and relief of products of combustion from the constant and safety pilot burners. To protect the constant pilot burner 26 against outage, the shield 3 may be perforate therebelow as at 28.

With reference now particularly to Fig. 6 of the drawings, the apparatus described is arranged in the following manner to be effective between a fuel source X such as a gas manifold, and a main burner B for control of the latter.

which leads to the main burner B from the source X, by way of a main valve 31 ahead of the safety valve. The main valve 31 may be a manual valve as indicated or might be timer or thermostat controlled, as well known in the art. A safety pilot gas line 32 leads to the safety pilot valve 18 subject to the main valve 31, as from the line 30 ahead of the main burner safety valve 1. A line 33 leads from the source X to the constant pilot valve 19, and may include a needle device 34 providing fine adjustment of constant pilot gas to a very small amount.

Operation will be as follows, commencing with the apparatus shut down or "cold," all the described valves being closed:

To light the constant pilot 26 a match may be applied to the exposed leg of the secondary thermally responsive unit 4b, which will cause this unit to open the valve 19 and admit gas to the constant pilot burner, which gas will be ignited by the match. Or the operator might manually open the valve 19 by manipulation of the yoke 23, ignite the constant pilot burner and allow the latter to heat the secondary unit 4b to maintain the valve 19 in open position before releasing the yoke 23.

As the constant pilot valve 19 opens, so also does the safety pilot valve 18, but no gas flows to the safety pilot burner 2 because the main valve 31 is closed.

When thereafter it is desired to operate the main burner B, the valve 31 is opened. This admits gas to the main burner line 30 ahead of the safety valve 1 but, since this valve is closed, no gas yet reaches the main burner.

However, the safety pilot valve 18 being open, gas flows to the safety pilot burner 2 by way of the lines 32 and 25. The safety pilot burner has immediate ignition from the constant pilot burner 26. Operation of the safety pilot burner 2 energizes the primary unit 4a and causes opening of the safety valve 1 to admit gas to the main burner B, which gas has immediate ignition from the safety pilot 2.

Energization of the primary unit 4a by the safety pilot burner moves the secondary unit 4b slightly farther from the yoke 23.

Assuming the automatic control parts to be located within the combustion chamber of the main burner B, as within a baking oven indicated by the broken line BB in Fig. 6, ambient temperature to which the automatic control parts are subject will rise. This may cause still further movement of the secondary unit 4b from the yoke 23 because of its bi-metal construction.

Should ignition of the safety pilot burner 2 extinguish the minute flame of the constant pilot 26, reignition at the constant pilot burner may result from the continued operation of the safety pilot burner, which is of substantially greater relative capacity.

While the safety pilot burner 2 is operating and energizing its primary thermally responsive unit 4a, its effectiveness through the secondary thermally responsive unit 4b maintains the valves 18 and 19 open regardless of outage at the constant pilot burner 26.

Should such reignition of the constant pilot burner not so occur, nevertheless the main burner B will remain in operation so long as the safety pilot burner 2 does, both however being subject at all times to the main valve 31.

Should the safety pilot burner 2 cease operation from any cause, its outage will deenergize its thermally responsive unit 4a and close the safety valve 1 to discontinue operation of the main burner B, even though the main valve 31 remain open. Safety effect of the safety pilot burner 2, upon the main burner B, through the safety valve 1, is always present, because the primary unit 4a is independent of ambient temperature.

After extinguishment of the safety pilot burner 2 for any reason, the constant pilot burner 26 normally remains in operation so that demand for operation of the

main burner B may be satisfied by recycling upon re-opening of the main valve 31.

However, should the constant pilot burner 26 have become extinguished, the secondary thermally responsive unit 4b will eventually close both valves 18 and 19, and the latter will remain closed until reestablishment of the constant pilot burner. If the secondary unit 4b is of bi-metal construction as described, and should the ambient temperature of the automatic control parts be high at the time of extinguishment of the constant pilot burner, more than will be required to close the valves 18 and 19, nevertheless they will eventually be closed and the entire apparatus consequently automatically shut down.

During such period of high ambient temperature, coincident with constant pilot outage before the valve 18 closes, manual reignition of the constant pilot burner is facilitated because its source of gas is continued, if the secondary unit 4b is somewhat responsive to ambient temperature as described.

High ambient temperature from continued operation of the main burner necessarily tends somewhat to distort relationships among the relatively delicate automatic control parts. The described provision of some ambient temperature effect upon the secondary unit 4b may serve as compensation to prevent malfunctioning shut down under such conditions.

However, it will be appreciated that by employment of the same metal in both legs of the secondary unit 4b, an advantage will be had in earlier shut down of the valves, on outage of the pilot 26 at high ambient temperatures.

It is to be noted that in operation of the unitary control device shown in Figs. 1 to 4, all three of its valves 35 and also the safety pilot burner, functionally are essentially under automatic control of the constant pilot burner. The operation of the pilot burner is essentially a prerequisite to the subsequent normal automatic operation of the other elements of the device, which are interconnected with it as described.

Structurally, the interrelation of the two pilot burners and three automatic valves is had and positively maintained by three common rigid base structures of the single base casting A plus the shield 3 rigidly associated therewith.

Also, it will be apparent that the unitary control device may be conveniently installed or removed for replacement as a single element of the control system in which it serves.

I claim:

1. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged to cause closing of both said pilot valves, upon outage of said constant pilot burner and said safety pilot burner.

2. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means

thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged to cause closing of both said pilot valves, upon outage of said constant pilot burner and said safety pilot burner, said means thermally responsive to said constant pilot burner being arranged to have movement away from said pilot valves when energized by operation of said constant pilot burner.

3. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged to cause closing of both said pilot valves, upon outage of said constant pilot burner and said safety pilot burner, said means thermally responsive to said constant pilot burner being arranged to have lost motion relative to said pilot valves when said means thermally responsive to said safety pilot burner is energized by operation of said safety pilot burner.

4. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged to cause closing of both said pilot valves, upon outage of said constant pilot burner and said safety pilot burner, said means thermally responsive to said constant pilot burner being arranged to have movement in pilot valve opening direction responsive to its energization by operation of said constant pilot burner, and to have further movement in said direction responsive to energization of said means thermally responsive to said safety pilot burner by operation of said safety pilot burner.

5. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner

arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged for movement in one direction to cause closing of both said pilot valves, upon outage of said constant pilot burner and said safety pilot burner, said means thermally responsive to said constant pilot burner being arranged to have movement in the opposite direction dependent upon its energization by operation of said constant pilot burner and also dependent upon rise in its own ambient temperature.

6. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner arranged to have movement in one direction to cause closing of both said pilot valves, upon outage of said constant pilot burner and said safety pilot burner, and to have movement in the opposite direction dependent incrementally upon its energization by operation of said constant pilot burner, upon the energization of said means thermally responsive to said safety pilot burner by operation of said safety pilot burner, and upon increase in its own ambient temperature.

7. A dual thermally responsive device of the class described comprising a pair of thermally responsive units, each of elongated form adapted for lateral deflection to produce movement of a relatively free end when mounted at its opposite extremity as a base end, one of said units constituting a primary unit and being of a type responsive to temperature differential between portions intermediate its ends and unresponsive to ambient temperature, the other of said units constituting a secondary unit, and being of a type responsive to ambient temperature, the base end of said secondary unit being secured to said primary unit at a location removed from the base end of the latter, whereby the free end of said secondary unit will have movement differentially responsive to ambient temperature and to said primary unit.

8. A dual thermally responsive device of the class described comprising a pair of thermally responsive units, each unit having a pair of elongated members generally of strip form disposed alongside each other in facing relation, the members of said pair having portions intermediate their ends arranged in spaced relation to each other and interconnected portions endwise therebeyond, one of said units constituting a primary unit, its said members being of the same material and their said endwise portions being integrally interconnected, whereby one end portion of said primary unit may be mounted to serve as a base end, and the other end portion serve as a movable end responsive to temperature differential between the intermediate portions of its members and independent of ambient temperature, the other of said units constituting a secondary unit, its said members being of materials of different coefficients of expansion, one of said endwise portions of said secondary unit being mounted on one of said members of said primary unit at said intermediate portion thereof, whereby to serve as a base end for said secondary unit, with the other end portion as a movable end, whereby said mov-

able end of said secondary unit will have movement differentially responsive both to ambient temperature and to temperature differential between the intermediate portions of its members, and also to movement of said primary unit.

9. A dual thermally responsive device of the class described comprising a pair of thermally responsive units, each unit having a pair of elongated members generally of strip form disposed alongside each other in facing relation, the members of said pair having portions intermediate their ends arranged in spaced relation to each other and interconnected portions endwise therebeyond, one of said units constituting a primary unit, its said members being of the same material and their said endwise portions being integrally interconnected, whereby one end portion of said primary unit may be mounted to serve as a base end and the other end portion serve as a movable end responsive to temperature differential between the intermediate portions of its members and independent of ambient temperature, the other of said units constituting a secondary unit, one of its said members being integral with said primary unit, and the other of a material of different coefficient of expansion, an endwise portion of the integral member of said secondary unit being joined to one of said members of said primary unit at said intermediate portion thereof whereby to serve as a base end for said secondary unit, with the other end portion as a movable end, whereby said movable end of said secondary unit will have movement differentially responsive both to ambient temperature, and to temperature differential between the intermediate portions of its members, and also to movement of said primary unit.

10. In means for controlling operation of a main gas burner from a fuel source therefor, and including a main valve, a safety valve, and a main gas line leading from said fuel source to said main gas burner by way of said main and safety valves successively, a safety pilot burner arranged in igniting relation to said main burner, means thermally responsive to said safety pilot burner for actuating said safety valve, whereby operation of said main gas burner is subject to operation of said pilot burner, a pilot gas line for said safety pilot burner arranged to be subject to said main valve, a constant pilot burner arranged in igniting relation to said safety pilot burner, a gas line for said constant pilot burner independent of said main valve, a pilot valve in said safety pilot gas line, a pilot valve in said constant pilot gas line, and means thermally responsive to said constant pilot burner

arranged to cause closing of both said pilot valves, upon outage of said constant pilot burner and said safety pilot burner, enclosure means arranged about said main, safety pilot and constant pilot burners, their said safety, safety pilot and constant pilot valves respectively, and said thermally responsive means, to provide a combustion chamber for said burners within which ambient temperature is affected by burner operation, said means thermally responsive to said constant pilot burner being arranged to have movement in the direction for opening of said pilot valves dependent upon its energization by operation of said constant pilot burner and also dependent upon increase in said ambient temperature.

11. A unitary control device for the purpose described comprising main burner safety valve means, safety pilot burner means, safety pilot valve means arranged for control of said safety pilot burner means, constant pilot burner means for ignition of said safety pilot burner means, and constant pilot valve means arranged for control of said constant pilot burner means, all of said means including parts which are portions of a common base structure, and thermally responsive means mounted on said base structure and arranged for control of said main burner safety valve means by said safety pilot burner means, and also arranged for control of both of said safety pilot valve means and said constant pilot valve means by said constant pilot burner means.

12. A unitary control device for the purpose described comprising main burner safety valve means, safety pilot burner means, safety pilot valve means arranged for control of said safety pilot burner means, constant pilot burner means for ignition of said safety pilot burner means, and constant pilot valve means arranged for control of said constant pilot burner means, all of said means including parts which are integrally related portions of a common base structure, and thermally responsive means mounted on said base structure and arranged for control of said main burner safety valve means by said safety pilot burner means, and also arranged for control of both of said safety pilot valve means and said constant pilot valve means by said constant pilot burner means.
